ELECTRIC LIGHT BULB

Max Bloese, Chicago, Ill.

Application November 14, 1950, Serial No. 195,655

4 Claims. (Cl. 315—73)

1

This invention relates to electric lighting, and more particularly to an electric light bulb including an internal structure for selectively opening and closing the bulb filament circuit in accordance with different positions of the bulb.

An object of this invention is to provide an electric light bulb which includes an internal structure particularly adapted to complete the bulb filament circuit in response to the movement of the bulb to an upwardly inclined position.

Another object of this invention is to provide an electric light bulb which includes a mass of electrically conductive material, such as mercury, loosely supported within the bulb for selectively completing the bulb filament circuit in accordance with the position of the bulb.

A still further object of this invention is to provide an electric light bulb of the type described which is particularly adapted to be supported on the trunk door of an automobile, whereby movement of the trunk door to the open position completes the filament circuit for the bulb to thereby illuminate the automobile trunk.

A still further object of this invention is to provide an electric light bulb including an internal structure for selectively opening and closing the bulb filament circuit which is relatively simple in structure and cheap to manufacture.

The above and still further objects and advantages of the present invention will become apparent upon consideration of the following detailed description of the invention when taken in conjunction with the accompanying drawings, wherein:

Figure 1 is a perspective view of the electric light bulb of the present invention shown supported on a female receptacle carried by the trunk door of an automobile; and

Figure 2 is an enlarged elevational view, with parts broken away and shown in section, of the electric light bulb of the present invention shown supported in the female receptacle of the trunk door with the trunk door in a closed position with respect to the trunk.

Referring now more particularly to the drawings, wherein like numerals have been used throughout the several views to designate like parts, there is shown the electric light bulb of the present invention, generally designated by the reference numeral 10, which is adapted to be mounted in a female receptacle 11 of the type including bayonet slots 12 and 13 for movement from various downwardly inclined positions to an upwardly inclined position. As clearly shown in Figures 1 and 2, the female light bulb receptacle 11 is supported by means of a bracket 14 on the swingable trunk door 15 of the automotive vehicle 16. The trunk door 15 is shown in the open position in Figure 1, wherein the light bulb 10 is supported in an upwardly inclined position and is shown in the closed position, Figure 2, wherein the light bulb is supported in a downwardly inclined position.

Electric light bulb 10 of the present invention includes a base 20 having spaced insulated termi-

2

nals illustrated as the electrically conductive shell 21 and the centrally disposed base terminal 22. The shell 21 is in the form of a cylindrical sleeve open at both ends and having one end turned inwardly to form an annular flange 23. Supported within the shell 21 is an insulator 24 which carries the base terminal 22 and is formed with an annular shoulder 25, the shoulder embracingly engaging the annular flange 23. Projecting outwardly from opposed points of the shell 21 are the lugs 26 and 27 which are receivable within the bayonet slots 12 and 13 of the female receptacle 11 for effecting the securing of the shell to the receptacle 11 in a position wherein the base terminal 22 contacts the terminal 28 of the female receptacle 11. The terminal 28 of the receptacle 11 is electrically connected to a suitable source of electrical energy, such as the automobile battery, by means of the wire 29.

Carried by the base 23 is an evacuated envelope 30 including a globe section 31 and a constricted or closed neck section 32 forming a support 33.

Disposed in the envelope are a pair of spaced lead-in wires 34 and 35 each of which has one end secured to the support 33 of the envelope 30. Disposed within the globe section 31 of the envelope 30 is a filament 36 which is electrically connected between the free ends of the lead-in wires 34 and 35.

The securing of the neck section 32 of the envelope 30 in the shell 21 of the base 20 is effected by means of the basing cement 37 which substantially surrounds the neck section 32 of the envelope and fills the interior of the shell 21. It is to be noted that the mass of basing cement 37 spaces the supported end of the envelope 30 from the insulator 24 and maintains the shoulder 25 of the insulator in contact with the annular flange 23.

Suitable means connect the end of the lead-in wire 34 carried by the support 33 to the base terminal 22. As clearly illustrated in Figure 2, the means for connecting the filament lead-in wire 34 to the base terminal 22 embodies a length of connecting wire 39 which is formed integrally with or secured to the filament lead-in wire 34 and is embedded in the insulator 24 and the mass of basing cement 37.

Carried by the support 33 of the envelope 30 is a contact 40 which has one end connected to the outer conductive shell 21 and has the other end projecting into the envelope contiguous to and spaced from the secured end of the lead-in wire 35.

Freely supported within the globe section 31 of the envelope 30 is a mass of an electrically conductive material, such as mercury, the mass or globule being designated by the reference numeral 41. The mass of mercury 41 is movable into bridging and contacting relation with respect to the contact 40 and the lead-in wire 35 in response to the movement of the base 20 into the upwardly inclined position. When the mass of mercury 41 bridges the contact 40 and the lead-in wire 35, an electrical circuit is completed for the

filament 36 of the light bulb 10. The filament circuit includes the lead-in wire 34 which is electrically connected to the base terminal 22, the filament 36, the lead-in wire 35, the mass of mercury 41, the contact 40, and the outer conductive shell 31. The outer conductive shell 31 is in contact with the grounded body of the female receptacle 11 and the base terminal 22 is in contact with the terminal 28 of the female receptacle to thereby complete the electrical circuit for the bulb.

Surrounding a substantial portion of the lead-in wire 34 contiguous to the secured end thereof is an insulating sleeve 42 which maintains the mass of mercury 41 out of short circuiting contact between the pair of lead-in wires 34 and 35. As illustrated, the insulating sleeve 42 may be formed integrally with the envelope 30.

For using the electric light bulb of the present invention on the trunk door 15, the lugs 26 and 27 are engaged in the opposed bayonet slots 12 and 13 of the female receptacle 11. When the trunk door 15 is in the closed position illustrated in Figure 2, the mass of mercury 41 will be supported in the lowermost portion of the globe section 31 of the envelope 30. Upon movement of the trunk door 15 to the open position illustrated in Figure 1, the mass of mercury 41 will move into a position bridging and contacting the lead-in wire 35 and the contact 40 to thereby complete the filament circuit for the bulb.

Although only one embodiment of the electric light bulb of the present invention has been illustrated, it is readily apparent that numerous modifications can be made without departing from the spirit of the invention as set forth in the appended claims.

What I claim is:

1. An electric light bulb comprising a base adapted to be mounted in a female receptacle for movement from various downwardly inclined positions to an upwardly inclined position, said base including an electrically conductive shell, an insulator disposed within said shell and supported therein, and a base contact carried by said insulator exteriorly of said shell, an evacuated envelope including a closed neck section forming a support carried by said base, a pair of laterally spaced lead-in wires disposed longitudinally within said envelope and each having one end secured to said support, a filament connected between the other ends of said pair of lead-in wires, means connecting said one end of one of said lead-in wires to said base contact, another contact carried by said support and having one end connected to said conductive shell and having its other end projecting laterally into said envelope contiguous to and spaced from said one end of the other of said lead-in wires, and a mass of electrically conductive material freely contained within said envelope and movable into bridging and contacting relation with respect to said other contact and said other lead-in wire in response to the movement of said base into said upwardly inclined position.

2. In an electrical lamp, a base comprising an exterior conductive shell containing an insulator, a base contact on said insulator exposed at one end of the shell, a bulb mounted on the opposite end of the shell, a pair of longitudinally extending lead-in wires projecting into the bulb from said insulator, said lead-in wires being in laterally spaced relation, a filament connected between the ends of said wires remote from the insulator, conductive means connecting one of said

wires to said base contact, the other wire being unconnected with said base contact and said shell, another contact carried by said insulator and positioned within the bulb in laterally spaced relation to the other lead-in wire, and a mass of conductive fluid material freely contained in said bulb for bridging said other contact and said other lead-in wire when the bulb is uptilted above the base, said mass being remote from said other contact and said other lead-in wire in down tilted positions of the bulb.

3. In an electrical lamp, a base comprising an exterior conductive shell containing an insulator, a base contact on said insulator exposed at one end of the shell, a bulb mounted on the opposite end of the shell, a pair of longitudinally extending lead-in wires projecting into the bulb from said insulator, said lead-in wires being in laterally spaced relation, a filament connected between the ends of said wires remote from the insulator, conductive means connecting one of said wires to said base contact, the other wire being unconnected with said base contact and said shell, another contact carried by said insulator and positioned within the bulb in laterally spaced relation to the other lead-in wire, and a mass of conductive fluid material freely contained in said bulb for bridging said other contact and said other lead-in wire when the bulb is uptilted above the base, said mass being remote from said other contact and said other lead-in wire in down tilted positions of the bulb, said other contact being located at the side of said other lead-in wire from said one lead-in wire.

4. In an electrical lamp, a base comprising an exterior conductive shell containing an insulator, a base contact on said insulator exposed at one end of the shell, a bulb mounted on the opposite end of the shell, a pair of longitudinally extending lead-in wires projecting into the bulb from said insulator, said lead-in wires being in laterally spaced relation, a filament connected between the ends of said wires remote from the insulator, conductive means connecting one of said wires to said base contact, the other wire being unconnected with said base contact and said shell, another contact carried by said insulator and positioned within the bulb in laterally spaced relation to the other lead-in wire, and a mass of conductive fluid material freely contained in said bulb for bridging said other contact and said other lead-in wire when the bulb is uptilted above the base, said mass being remote from said other contact and said other lead-in wire in down tilted positions of the bulb, said other contact being located at the side of said other lead-in wire from said one lead-in wire having insulating means extending longitudinally therealong from said insulator toward said filament, said insulating means serving to prevent bridging of said lead-in wires by said mass of conductive fluid in an uptilted position of the bulb.

MAX BLOESE.
